UNITED STATES PATENT OFFICE.

CLINTON W. HOUGH, OF BOONVILLE, NEW YORK, ASSIGNOR TO WIRED RADIO, INC., OF NEW YORK, N. Y., A CORPORATION OF DELAWARE.

WIRED RADIO RECEIVING APPARATUS.

Application filed February 25, 1924. Serial No. 694,817.

To all whom it may concern:

Be it known that I, CLINTON W. HOUGH, a citizen of the United States, residing at Boonville, in the county of Oneida, State of New York, have invented certain new and useful Improvements in Wired Radio Receiving Apparatus; and I do hereby declare the following to be a full, clear, and exact description of the invention, such as will enable others skilled in the art to which it 10 pertains to make and use the same.

This invention relates to high frequency signal receiving apparatus and, more particularly, receiving apparatus for use in so-called wired wireless systems.

In wired wireless broadcasting systems wherein broadcast programs are transmitted over electric power distribution systems by means of high frequency carrier current the 20 receiving apparatuses are connected to transmission lines of fairly high voltage—for example, 110 volts. In the construction of apparatus of this character it is necessary to carefully guard against the possibility of 25 electrical shocks to the subscribers of the broadcasting service as well as to guard against fire hazard.

Receiving apparatus of the character referred to is usually distributed on a monthly 30 rental basis instead of by outright sale and for this reason it is necessary to take precautions against the apparatus being tampered with by the subscribers.

The principal objects of this invention are, 35 therefore to provide a wired wireless receiving apparatus in which all danger of electrical shock being transmitted to the subscriber is obviated; in which the fire hazard is reduced to a minimum; and in which the 40 more delicate electrical elements and connections are inaccessible to the subscriber.

According to the preferred embodiment 45 of this invention as illustrated in the accompanying drawings and the detailed description hereinafter, all of the electrical elements and their connections, with the single exception of a fixed crystal detector, are mounted and completely enclosed within a receptacle which is so constructed that it 50 is practically inaccessible to the subscriber.

The circuit arrangement comprises a primary circuit and a secondary circuit which are inductively associated. The terminals

of the primary circuit are arranged to be connected across an electric light line while 55 the secondary circuit includes the telephone receivers. In order to prevent the relatively high voltage from the electric light line reaching the telephone receivers and thus subjecting the subscriber to danger of being 60 shocked, the two circuits, that is primary and secondary, are separated by means of a partition of dielectric material of substantial thickness which is capable of withstanding 65 many times the voltage on the electric light line. For the purpose of guarding against fire hazards, the inductance coil included in the primary circuit is so designed that in the event of its becoming connected directly 70 across the electric light line it will quickly burn out like a fuse. There is therefore, no danger of a substantial amount of heat being developed in this coil such as would be likely to result in fire.

Other features of this invention reside in 75 the details of construction all of which are clearly described hereinafter.

Referring to the accompanying drawings, Fig. 1 is an elevational view of a wired wireless receiving apparatus in accordance with the preferred embodiment of this invention,

Fig. 2 is a plan view of the apparatus shown in Fig. 1,

Fig. 3 is a vertical cross-sectional view of the apparatus taken along the line 3—3 of Fig. 4.

Fig. 4 is a vertical cross-sectional view taken along the line 4—4 of Fig. 3,

Fig. 5 is a vertical cross-sectional view taken along the line 5—5 of Fig. 6,

Fig. 6 is a vertical cross-sectional view taken along the line 6—6 of Fig. 5,

Fig. 7 is a plan view of the apparatus with the cover of the receptacle removed.

Fig. 8 is a plan view similar to Fig. 2 except that it shows only the top of the receptacle—the control dial and crystal detector being omitted.

Fig. 10 is a fragmentary elevational view showing the crystal detector and

Fig. 11 is a circuit diagram.

The circuit arrangement here employed as shown in Fig. 11 comprises a primary circuit and a secondary circuit. The primary circuit comprises an inductance coil 1 and a variable condenser 2 while the sec-

ondary circuit comprises an inductance coil 3, crystal detector 4, fixed condenser 5, and a telephone headset 6. The electrical elements and their connections with the exception of the crystal detector 4, and, of course, the telephone headset 6, are enclosed within a receptacle which includes a base 7 and a cover 8, both of which are preferably made of pressed sheet metal. The crystal detector 10 is mounted on the outside of the receptacle for the reason that it may be desirable or necessary for the subscriber to change it from time to time should it get out of adjustment.

15 The base 7 is made in two parts, 7^a and 7^b, the first of which forms a false bottom as clearly shown in Figs. 3 to 6 inclusive.

Three partition members, 9, 10 and 11 each consisting of a plate of dielectric material such as bakelite are secured to the false bottom 7^a by means of screws 12 as may be clearly seen from an examination of Figs. 3 to 6 inclusive; the screws 12 are inaccessible from the exterior of the receptacle because of the fact that the heads are concealed by the base member 7^b. Members 7^a and 7^b are secured together by means of rivets 13, and are held in proper spaced relation by separators 14. Inductance coils 1 and 3 of the primary and secondary circuits respectively, are disposed on opposite sides of the partition 9 in inductive relation one to the other. These coils are preferably of the honeycomb type having central openings 1^a and 1^b respectively and are supported on rectangular pieces of dielectric material 15 and 16 which are secured to partitions 10 and 11 by means of roundhead screws 17 and 18. Each of the partitions 10 and 11 is provided with two tapped holes 19 and 20, one above the other, into either of which screws 17 and 18 may be inserted. Additional tapped holes may be provided if desired. These holes serve to permit the coils 1 and 3 being moved up and down for changing the inductive coupling therebetween.

40 The lead-in cord 21, to one end of which the screw plug 22 is attached, is passed through an insulating bushing 23 to the interior of the receptacle and is made fast to partition 10 in the manner clearly shown in Figs. 3 and 5.

45 The primary variable condenser 2 is of the rotary type and is secured to the tops of the partition members 9, 10 and 11. The plates of this condenser are completely enclosed within a casing of insulating material and a rotatable shaft 24 for operating the condenser extends to the outside of the cover 8. A knob and dial 25 is secured to the end of shaft 24 by means of a screw 26. When the screw 26 is in place the aperture 27 in the knob 25 thru which it passes is filled with sealing wax or some other suitable compound so that the end of the screw is not

accessible. The cover 8 of the receptacle is so formed that it underlies the dial 25 and is so arranged that a tool or wire cannot be readily passed under the dial to the interior of the apparatus. In order to remove the cover 8 from the base 7 and thus gain access to the interior of the apparatus, it is necessary to first remove screw 26 and then the knob and dial 25 after which the cover 8 may be lifted off the base. By reason of the fact that the aperture 27 is sealed up with wax of the same color as the knob 25 the method of gaining access to the interior of the apparatus is concealed from the subscriber. The two conductors of cord 21 are connected respectively to one terminal of condenser 2 and to one terminal of inductance coil 1 while the remaining terminals of coil 1 and condenser 2 are connected together. The fixed condenser 5 is provided with a pair of Faunestock clips connected to its terminal and to which the tips of the telephone cord are attached. Condenser 5 is secured to partition 11 by means of bolt 29 and nut 30. The metal straps 31 and 32 to the upper ends of which the fixed crystal detector 4 is attached are secured to partition 11 by means of bolts 29 and 33. Since the bolts 29 and 33 pass through both straps 31 and 32 it is necessary to insulate these bolts from at least one of the straps. This is accomplished by providing insulating bushings and washers between the straps and bolts.

50 In order to prevent short circuiting straps 31 and 32 through the metal cover 8, soft rubber sleeves 34 and 35 are provided. These sleeves may be easily slipped off the straps whenever the cover 8 is to be removed.

55 In operation, screw plug 22 is inserted in an ordinary lamp socket thereby connecting the primary circuit across the two sides of the line. Knob 25 is rotated for varying the capacity of condenser 2 in the primary circuit. This affects tuning of the primary circuit to the frequency of the high frequency carrier waves on which the broadcast signals are transmitted. The secondary circuit is not tuned in so far as it is affected by the tuning of the primary circuit.

60 Inductance coil 1 is of relatively fine wire so that in the event of a break-down of condenser 2 the current which would pass will quickly burn out coil 1 and open the primary circuit. The possibility of any dangerous voltage being transmitted to the secondary circuit and thence to the telephone head set is obviated by the provision of partition 9 which separates the primary and secondary circuits. This partition is preferably of a good dielectric material and is of ample thickness to withstand a much greater voltage than is ever likely to be applied to the primary circuit.

65 I claim:

1. In high frequency signal receiving apparatus, a receptacle comprising a base and a cover therefor, a variable electrical device mounted within said receptacle, a rotatable shaft for said device extending to the exterior of said receptacle, a knob and dial secured to said shaft, said dial being undercut at its lower face and said cover having an annular depression in the top thereof terminating in an annular bead extending upwardly to a position within the undercut face of said dial for obstructing a straight line passage between said dial and cover, said knob and dial being operable to prevent the removal of said cover from said base, said receptacle completely enclosing said device so that it is inaccessible from the exterior of the receptacle.
2. In high frequency signal receiving apparatus, a receptacle comprising a base, a cover fitting said base and forming therewith a substantially enclosed receptacle, a partition of dielectric material supported on said base and enclosed within said receptacle, a primary circuit comprising an inductance coil, said coil being mounted on one side of said partition, a secondary circuit comprising a second inductance coil mounted on the other side of said partition in inductive relation to said first-mentioned inductance coil, a variable electrical device having a rotatable shaft, said device being mounted within said receptacle with said shaft extending to the exterior thereof through an aperture in said cover, a dial secured to the exterior end portion of said shaft, said dial overlying a portion of said cover, thereby preventing removal of said cover from said base, attaching means for securing said dial to said shaft, and means for enclosing said attaching means to prevent unauthorized tampering therewith.
3. In high frequency signal receiving apparatus, a receptacle comprising a base having a bottom member and a false bottom member, partitions of dielectric material mounted on said base and secured to said false bottom member by means of screws which extend through said false bottom member, said bottom member covering said screws so as to prevent access thereto, electrical elements mounted on said partitions, said elements including an adjustable element having a rotatable shaft, said receptacle including a cover which fits on said base and cooperates therewith to form a substantially complete enclosure for said electrical elements, said shaft projecting through an aperture in said cover to the exterior thereof, a dial mounted on the end portion of said shaft and overlying a portion of said cover, means for securing said dial to said shaft, said dial having an aperture to permit the insertion of said means, said aperture being sealed after the insertion of said means.
4. A wired radio receiving apparatus comprising in combination a metallic casing, an insulated entrance for power supply conductors at one side of said casing, sets of radially positioned dielectric partition members within said casing, means for anchoring the power supply conductors on one of said partition members, inductance coils carried by two of said partition members and substantially insulated one from the other by another of said partition members, and variable tuning means supported by said partition members and operable from the exterior of said casing.
5. A wired radio receiving apparatus comprising in combination a metallic casing, an insulated entrance for a power supply line in one wall of said casing, a pair of radially extending dielectric partitions within said casing, a diametrically disposed dielectric partition member separating the adjacent ends of said partition members, a primary coil carried by one of said first mentioned partition members, a secondary coil carried by the other of said first mentioned partition members, said coils being substantially insulated one from the other by said diametrically extending partition member, and tuning apparatus carried by the extremities of said partition members and operable from the exterior of said casing.
6. Wired radio receiving apparatus comprising in combination a metallic casing, an insulated entrance for a power supply line carried in one wall of said casing, a pair of radially positioned dielectric partition members within said casing, a diametrically disposed partition member extending between adjacent ends of said pair of partition members, vertically adjustable coil supports carried by adjacent ends of said pair of partition members and inductance coils positioned on the adjacent ends of said pair of partition members and arranged to be selectively set in position with respect to each other, tuning apparatus carried by said partition members, and means for operating said tuning apparatus from the exterior of said casing.
7. Wired radio receiving apparatus comprising in combination a fire-proof casing, an insulated entrance for power line conductors in one wall of said casing, a primary circuit, a secondary circuit, each of said circuits including an inductance coil and said primary circuit having a condenser in series with the inductance coil therein, a pair of dielectric partition members radially positioned within said casing, a diametrically disposed partition member positioned between adjacent ends of said pair

of partition members, said pair of partition members carrying said inductance coils at their adjacent edges substantially insulated one from the other by said diametrically extending partition member, the inductance disposed in said primary circuit having such value that upon failure of the dielectric properties of the condenser in the

said primary circuit the inductance therein becomes ruptured for protecting said wired 10 radio receiving apparatus against destructive effects from the current existent in said power supply line.

In testimony whereof I affix my signature.

CLINTON W. HOUGH.
